CANE MILL

Carl F. Schnuck, New Haven, Conn., assignor to
 Farrel-Birmingham Company, Incorporated,
 Ansonia, Conn., a corporation of Connecticut

Application January 26, 1945, Serial No. 574,741

12 Claims. (Cl. 100—47)

1

This invention relates to cane mills, and more particularly to cane mills of the three-roller type employed in the grinding of sugar cane.

The invention has to do especially with the provisions for controlling the flow of the cane juice in the regions adjacent the ends of the rolls. When the cane passes through the mill, a large quantity of juice is expressed from it, and this drops or flows to a collecting pan below the rolls. As gravity carries the juice in a downward direction, there is no particular problem presented in keeping the juice out of the bearings of the top roll, but in the case of the cane roll and the bagasse roll there has been a very definite problem arising from the juice coming into contact with the smooth working surfaces associated with the journals. The cane juice has a deleterious effect upon them, especially the journal portions of the steel roll shafts, resulting in pitting and increased wear. It may be necessary from this cause to replace one or more of the lower rolls, and this is especially objectionable if it has to be done at a time when cane is coming into the mill to be ground because of the deterioration which takes place in the waiting cane.

One of the objects of the present invention is to overcome these drawbacks by providing a cane mill having improved means for controlling the flow of juice in the regions adjacent the ends of the lower or side rolls.

Another object is to provide an improved juice guard assembly for use in connection with a cane-grinding roll.

In the accompanying drawings:

Fig. 1 is a side elevation of a cane mill embodying the invention;

Fig. 2 is a top plan view of a portion of the mill shown in Fig. 1;

Fig. 3 is an enlarged section on line 3—3 of Fig. 1;

Fig. 3A is a detail sectional view on a smaller scale, showing the arrangement of the end flange of the top roll with respect to the guard ring of the bagasse roll;

Fig. 4 is a section on line 4—4 of Fig. 3;

Fig. 5 is a detail section of certain parts illustrated in Fig. 4; and

Figs. 6 and 7 are perspective sectional details of the pressure ring and the sealing ring, respectively.

The mill illustrated is of the usual three-roller type, having the usual housings and having a cane roll, a top roll and a bagasse roll in the customary triangular arrangement. In the drawings, the cane roll is shown at 10, the top roll at

2

11, and the bagasse roll at 12. One of the housings is indicated in Figs. 1 and 2 at 13, and the juice pan arranged underneath the rolls is indicated at 14.

5 During the operation of the mill the side rolls 10 and 12 rotate on fixed axes, and the top roll has movement in a substantially vertical plane under the control of hydraulic devices, one of which is indicated at 15. These hydraulic devices 10 may be of any preferred form, and it is unnecessary to describe them in detail. At each end of the cane roll the shaft is carried by a bearing structure 16 adjustable horizontally by a screw 17 operating in a cap 18. Similarly, the bagasse 15 roll has at each end a bearing member 19 adjustable by a screw 20 operating in a cap 21.

At each end of the top roll 11 the same carries a laterally projecting flange 22. This flange cooperates with a guard flange carried by the cane 20 roll and also with a guard flange carried by the bagasse roll. The guard flanges of the cane roll and bagasse roll are similar, as well as the other juice-excluding means used in connection with these two rolls, and the structure used in connection with the bagasse roll is illustrated in the drawings as being typical. The bagasse roll has applied to each end a guard member in the form of a ring 23 carrying a guard flange 24 that overlaps the flange 22 in the manner shown in Fig. 3A. 25 The body of ring member 23 and its flange 24 provide in conjunction a trough 25 in which juice can flow, and from which juice can drop down into the pan 14.

30 The ring 23 is fastened to the end face of the bagasse roll by means of screws 26 having threaded shanks engaging threaded sockets 27 in the bagasse roll, the heads 28 of such screws being countersunk in the ring member. The ring member 23 is fitted tightly around the shaft 29 of the roll, and between the inner face of the ring 35 and the adjacent face of the roll a gasket 30 is interposed for preventing leakage of juice from the trough 25 toward the shaft. The flange 24 has a substantially straight wall lying at a small angle to a vertical plane directed transversely to the roll, so that the flange conforms substantially to the inclination of a proximate inclined surface 24A on flange 22. By this arrangement the trough 25 is gradually narrowed from the top of the trough to the bottom (Fig. 3A).

40 Lying against the outer face 31 of ring member 23 is an elastic sealing member 32. This sealing member is in the form of a ring having its inner surface lying against the shaft 29, and having an 45 end surface lying against the face of an end

flange 33 provided upon the bearing brass or liner 34. This liner 34 journals the roll, being made of special bearing metal and being fitted over the smooth journal portion 29^a with which the shaft 29 is provided. The flange 33, by being extended laterally from the inner end portion of the liner, provides a space around the larger cylindrical portion of shaft 29 in which the sealing ring 32 may be placed, with one side surface of the sealing ring against the guard ring and the other side surface against the liner.

The elastic sealing member 32 may advantageously be made of Neoprene or other elastic plastic material which will not be attacked by the juice acids. This member may have an opening 35 at the center for increasing its compressibility to a certain degree. It is held in place by a pressure member, indicated at 36, that is preferably in the form of a metal ring divided diametrically so as to be in two sections that are interconnected by suitable fastening members. In the form shown, the pressure ring comprises the sections 36' and 36'', and these sections are interconnected by fastening devices 37. The fastening devices 37 may be of the kind shown in Fig. 5, where section 36'' has an end shoulder 38 located near a deeper end shoulder 39 provided on the other section. In shoulder 39 is a tapped socket 40, and in shoulder 38 an untapped hole 41. A screw shank 42 entering the hole has its threads in engagement with the threads of socket 40. A nut 43 is screwed up on the screw shank to fasten the two sections together, and a lock nut 44 completes the assemblage. In this manner the two sections can be brought toward each other to exert the necessary pressure on the sealing member.

As will be noted from Fig. 4, it is preferred to form each of the sections 36', 36'' with a shoulder 38 at one end and a shoulder 39 at the opposite end. Thus all the ring sections which are supplied are interchangeable.

The pressure ring 33 may be rounded off at the outer part, as indicated at 36^a. At its inner part this ring is provided with a wedge whereby it is adapted to spread the sealing ring laterally, and in the form shown the entire inner face 45 of the pressure ring is in the form of an obtuse wedge having two surfaces that meet in the median plane of the ring, as indicated at 46. These surfaces may, as shown, present between them an angle of 155°, but this is mentioned merely by way of example. The sealing ring may, as in the example shown, be of approximately square cross section, presenting a normally cylindrical outer face engaged by the wedge-shaped portion of the pressure ring. The wedge on the pressure ring is pressed against and into the sealing ring so as to compress the latter to a certain extent and deform it and spread it laterally so that the side faces of the sealing ring are brought into sufficiently tight contact with their opposed surfaces to thereby prevent the ingress of juice or any other liquid to the larger cylindrical portion of the shaft. Thus this portion of the shaft, and the adjacent cylindrical portion of reduced diameter which forms the journal, are effectively protected against entry of any liquid into the space between the guard flange of the side roll and the associated bearing brass or liner.

The sealing ring in the form shown is made of one length of synthetic rubber strip, the ends of which are brought together and abutted, as shown at 47 in Fig. 4.

In the operation of the mill, the action of the

rolls upon the cane mat causes a large quantity of juice to be expressed from the cane and to flow over considerable portions of the roll surfaces. The rolls are usually grooved both lengthwise and transversely, as usual in sugar mill practice, but for clarity the grooving is omitted from the drawings. As above indicated, there is no particular problem of erosion in connection with the bearings of the top roll, this being due to the arrangement of the rolls. However, for the protection of the shafts of the lower rolls or side rolls from the cane juice, satisfactory measures are necessary, and these are provided by the present invention. It will be noted that the inclined flanges 24 of the lower rolls overhang to a considerable extent the sealing structure between the base portion or body of the guard flange and the adjacent bearing liner. Hence, if there is leakage or spilling of juice from the trough of the side roll over the lip provided by the flange 24, the liquid will, for the most part, be carried past the sealing means and against the outer surface of the bearing where it will do no harm, and in the event that there is any tendency to leakage between the liner of the bearing and the guard flange structure, this will be overcome by the sealing provisions previously described. Consequently the juice is effectively prevented from reaching the shaft and from entering the bearing.

It is, of course, noted that in the operation of the mill the sealing ring 32 rotates with the associated shaft by reason of its being clamped thereto, while the bearing liner, on the other hand, with which the sealing ring is in contact, remains in a fixed position. However, the rotation of the sealing ring in contact with the liner is not objectionable, there being no undue friction. This is particularly true where the sealing ring comprises rubberlike material, which is inherently slippery in the presence of moisture or oil. The journal portion of the shaft is supplied with oil for proper lubrication, and the lubricant tends to work out of the bearing and to make contact with the sealing ring, and this is one of the factors tending to impart slipperiness to that surface of the sealing ring which is in contact with the liner. The pressure against the liner is sufficient to create a seal, but not sufficient to create undue friction, this pressure being regulable by the adjusting means used in connection with the pressure ring. Owing to the provisions mentioned it is possible successfully to use a seal between the rotating guard member and the bearing liner, and, moreover, it is possible successfully to seal the space between the end face of the roll and the surface at the end of the bearing liner so as to prevent the access of juice to the journal portion of the shaft. In this connection it is important to note that, while the particular sealing means above described has many advantages, the invention in its broader phases is not restricted to the use of any particular material moving in contact with the liner provided the requisite sealing effect and the requisite amount of slip are present.

It will be apparent that, as the journal portions of the side rolls are effectively protected from the pitting or other destructive effect of the cane juice, the rolls can be maintained in operation for a longer time than previously without the need of repairs or replacements.

While only a single embodiment of the invention is shown in the drawings, it is to be understood that the invention may take many different forms and that various modifications and changes

may be made within the principles of the invention and the scope of the claims.

What I claim is:

1. In a cane mill, the combination of a top roll having an outstanding flange at the end for controlling the flow of juice, a lower roll coating with the top roll and carrying at the end a guard member presenting a juice trough in line with the flange of the top roll, said lower roll having an extended shaft with a journal portion, a bearing having a liner embracing said journal portion and spaced laterally from said guard member to provide a receiving space for a sealing member, an annular elastic sealing member in said space having an inner surface in engagement with a portion of the shaft surface, and a pressure ring exerting radially inward pressure on said sealing member whereby it is pressed laterally against the liner and against the associated guard member.

2. In a cane mill, the combination of a top roll having an outstanding flange at the end for controlling the flow of juice, a lower roll coating with the top roll and carrying at the end a guard member presenting a juice trough in line with the flange of the top roll, said lower roll having an extended shaft with a journal portion, a bearing having a liner embracing said journal portion and spaced laterally from said guard member to provide a receiving space for a sealing member, an annular elastic sealing member in said space having an inner surface in engagement with a portion of the shaft surface, and a pressure ring exerting radially inward pressure on said sealing member whereby it is pressed laterally against the liner and against the associated guard member, said pressure ring being shaped at its inner part to wedge into said sealing member.

3. In a cane mill, the combination of a top roll having an outstanding flange at the end for controlling the flow of juice, a lower roll coating with the top roll and carrying at the end a guard member presenting a juice trough in line with the flange of the top roll, said lower roll having an extended shaft with a journal portion, a bearing and spaced laterally from said guard member to provide a receiving space for a sealing member, an annular elastic sealing member in said space having an inner surface in engagement with a portion of the shaft surface, and a pressure ring exerting radially inward pressure on said sealing member whereby it is pressed laterally against the liner and against the associated guard member, said guard member presenting an inclined flange having a lip overhanging the pressure ring.

4. In a cane mill, a lower roll having a shaft provided with a cylindrical portion extended beyond the end of the roll body, said shaft having a cylindrical journal portion of reduced diameter extended from said first portion, a bearing for the roll having a liner embracing said journal portion and provided at the inner end with an outstanding flange projecting laterally beyond the first-mentioned cylindrical portion adjacent the outer end of said portion, a trough-presenting juice guard member fastened to the roll body at the end of the latter and in engagement with the first cylindrical portion, an elastic sealing ring embracing said first cylindrical portion between said last-named member and the flange of said liner, and a pressure ring exerting radially inward pressure against the sealing ring in order to seal the space between the guard member and the liner.

5. In a cane mill, a lower roll having a shaft

provided with a cylindrical portion extended beyond the end of the roll body, said shaft having a cylindrical journal portion of reduced diameter extended from said first portion, a bearing for the roll having a liner embracing said journal portion and provided at the inner end with an outstanding flange projecting laterally beyond the first-mentioned cylindrical portion adjacent the outer end of said portion, a trough-presenting juice guard member fastened to the roll body at the end of the latter and in engagement with the first cylindrical portion, an elastic sealing ring embracing said first cylindrical portion between said last-named member and the flange of said liner, and a pressure ring exerting radially inward pressure against the sealing ring in order to seal the space between the guard member and the liner, said pressure ring being made in sections and having a wedging portion engaging the sealing ring.

6. In a cane mill, a roll body, a shaft for said body having an extended cylindrical portion adjacent the end of the body and beyond said portion a cylindrical journal portion of reduced diameter, a bearing having a liner engaging said journal portion, an annular guard member fastened to the roll body and embracing said first cylindrical portion but leaving a space around said first cylindrical portion between the guard member and the inner end of the liner, an elastic sealing ring in said space, and means spreading said ring laterally to cause it to fill said space.

7. In a cane mill, a roll body, a shaft for the roll body extended beyond the end of the latter, a bearing for said shaft having a liner the inner end of which is positioned to leave a space between it and the end of the roll body, a trough-like guard member in a portion of said space and fastened to the roll body, and an annular sealing device in the remainder of said space.

8. In a cane mill, a roll body, a shaft for the roll body extended beyond the end of the latter, a bearing for said shaft having a liner the inner end of which is positioned to leave a space between it and the end of the roll body, a trough-like guard member in a portion of said space and fastened to the roll body, and an annular sealing device in the remainder of said space, said sealing device comprising an annular pressure ring and an elastic sealing ring held by said pressure ring in contact with the guard member, the shaft and the liner.

9. In a cane mill, a roll body, a shaft for the roll body extended beyond the end of the latter, a bearing for said shaft having a liner the inner end of which is positioned to leave a space between it and the end of the roll body, a trough-like guard member in a portion of said space and fastened to the roll body, and an annular sealing device in the remainder of said space, said sealing device comprising an annular pressure ring and an elastic sealing ring held by said pressure ring in contact with the guard member, the shaft and the liner, said guard member having an outstanding flange presenting a free edge or lip overhanging said pressure ring.

10. In a cane mill, a roll shaft, a roll body thereon, a bearing having a liner embracing a portion of the shaft, a guard flange member attached to the body adjacent the shaft, a deformable one-piece sealing ring around the shaft between the guard flange member and the liner, and pressure means for holding the sealing ring on the shaft and spreading it so

that it contacts the liner and the guard flange member.

11. In a cane mill, a roll body having an end face, a roll shaft having a cylindrical portion projecting from said face and a smaller cylindrical journal portion, a bearing having a liner embracing said journal portion, said liner having a flange at the end adjacent the roll body, and means for sealing the space around the larger cylindrical portion of the shaft between the liner and the roll body, secured to the roll body to rotate therewith and including a juice trough member, a packing member, making sealing contact with the juice trough member and slipping sealing contact with said flange, and a pressure ring holding the packing member on the shaft and exerting a spreading action on the packing member.

12. In a cane mill, the combination of an upper roll having a laterally extended end flange, a lower roll having a body with an end face, a shaft extended from said end face and having a journal portion spaced from said face, a bearing having a liner embracing said journal portion, said bearing being open at the end toward the lower roll, a trough-like annular guard mem-

ber around said shaft carried by said lower roll substantially in line with said end flange and having a lip over which liquid passes in moving in a direction away from the end of the lower roll body and toward the inner end of said bearing, and means for sealing the inner end of said bearing.
